UNITED STATES PATENT OFFICE.

ROBERT L. MONTGOMERY, OF FORT WORTH, TEXAS.

SHOW CASE.

Application filed June 29, 1925. Serial No. 40,291.

This invention relates broadly to store furniture, and has more particular reference to an improved show case.

More specifically speaking, the invention relates to a show case of knock down construction, permitting one or all of the parts to be disassembled for enlarging, reducing or completely disassembling for transportation purposes.

10 The principal object is to generally improve upon show cases, by providing one of greater durability, one which is exceedingly sanitary, attractive in appearance, much superior to the ordinary permanent case, 15 embodying wooden joints, and one which may be completely disassembled and crated in a compact condition for shipping.

One distinct feature is a metallic sectional casing, upon which the metal floor of the 20 case is adapted to rest, this metal floor being constructed to effectively accommodate the glass panel forming the major details of the invention.

Other features and advantages of the 25 invention will become apparent during the course of the following detailed description.

In the accompanying drawings, forming a part of this application, and in which like reference characters indicate corresponding 30 parts throughout the several views:

Figure 1 is a side elevation of a complete show case constructed in accordance with the present invention.

Figure 2 is a transverse section through the same.

Figure 3 is a fragmentary side view, showing a joint clamp.

Figure 4 is a detail section, taken on the plane of the line 4—4 of Figure 3, looking downwardly.

Figure 5 is a perspective view of one corner of the case, showing the construction of the top.

Figure 6 is a section through one of the corners showing the cornice construction more plainly.

Figure 7 is a perspective view of a portion of the cornice with the glass plates removed.

Figure 8 is a perspective view of the clamping device, shown in Figure 3.

Figure 9 is a perspective view of a portion of one corner of the base.

Considering first the construction of the base, and noting particularly Figures 2 and 9, it will be seen that the same is made

up of two side plates 1 and two end plates 2, both of which have their upper edges directed angularly inward to provide supporting flanges 3. One end of the end 60 plate 2 is directed at right angles, as at 4, and provided with bolt holes adapted to register with holes formed in the vertical portions of the side plate 1, whereby to permit the two plates to be detachably connected together.

Referring now to Figure 2, it will be seen that a metallic bottom 5 is provided, and this rests upon the supporting flanges 3, being connected thereto in any suitable 70 way. Formed integral with its bottom is a marginal upstanding flange 6. This flange extends all of the way around the bottom and on the rear side there are two additional flanges 7 and 8 employed to accommodate a 75 pair of sliding doors 9, by means of which access is had to the interior of the case. The other walls of the case are made up of glass panels 10 and these bear at their lower ends against the inner faces of the 80 flanges 6. The top 11 is also in the form, preferably, of a glass panel.

For the purpose of maintaining the panels in assembled relation, I provide special cornice constructions. In Figures 6 and 7 85 I have shown very plainly the construction of each cornice. First, I would call attention to the fact that the cornice is of a height to extend from the bottom 5 to the top edges of the glass panel, thus reinforcing the corners of the show case from top to bottom. Each cornice comprises inner and outer plates 12 and 13 respectively, the inner plate being somewhat smaller in size, but most plates having their ends disposed at 90 right angles to each other. The right angular portions are connected together by flattened portions 15 and it is obvious that when the two glass panels are brought between the two plates as shown in Figure 6, retaining bolts 16 are passed through the flattened portion 15 to maintain the parts in assembled form. In this connection, it will be noted that the angle irons 17 are employed for connecting the top panel 11 with the side 100 panel 10. Also, as shown in Figure 2, an appropriate spacer 18 is interposed between the doors 9 for maintaining them in the spaced relation shown. It is preferable to provide triangular corner caps 19, as shown 105 in Figure 5.

In instances where sectional side panels

are provided, as indicated in Figures 3 and 4, special clamping devices are utilized as shown in these figures. Confining attention here, it will be seen that the devices 5 simply comprise inner and outer metal strips 20 and 21 respectively, the outer strip being comparatively wide, and, by preference, having its vertical edges inturned upon themselves, as shown. The retaining bolt 22 10 may be utilized, if desired. The two vertical strips 20 and 21 may be connected together with horizontal or top strips 23 by angle brackets 24.

From the foregoing description and drawings, it is obvious that I have evolved and produced a novel structure wherein the feature resides more particularly in the fact 15 that it is possible to utilize side walls which are made of panels, in which instance the abutting edges of the two panels are connected together by clamping devices, such as shown in Figures 3 and 4. This protects the entire edges of the glass. If a case has been constructed of one size, and it is desired 20 to extend it in length, this may be done by removing one end wall 2 from the base, and providing additional glass, a bottom 25 5, etc. In this instance, the additional glass will be placed in abutting relation 30 with the original glass, and the special clamps shown in Figures 3 and 4 will be brought into play. The cornices will simply 35 be removed to the new end of the case and will be reused. Under this arrangement, the cases may be made of any length or height 40 and may be varied from time to time by simply ordering additional clamping strips and the like. Moreover, with a case of this kind, all of the clamping devices will be 45 made of sturdy metal, which may be nickel plated, enameled, baked, or otherwise treated to render them ornamental and sanitary in appearance. All of the metal strips may be arranged in a comparatively small packet and transported in a small crate. In

cases of a permanent nature, it is necessary to ship the entire case, thus making the crating necessarily expensive and inconvenient. With my arrangement, the retaining devices 50 of metal may be shipped separately, and the glass bought at a local establishment and the case assembled.

An advantage of this scope will undoubtedly be appreciated by those skilled in the art to which the invention relates. Furthermore, it is believed that a consideration 55 of the description in connection with the drawings will enable a clear comprehension of the invention to be obtained. Therefore, a more lengthy description is thought unnecessary.

While I have shown the preferred embodiment of the invention, it is to be understood that various changes in the size, shape, and arrangement of parts may be resorted 60 to, without departing from the spirit of the invention or the scope of the appended claim.

Having thus described my invention, what I claim as new is:

In a show case construction, a frame comprising spaced parallel side plates, and a pair of end plates, said end plates having their ends disposed inwardly and adapted to be detachably secured with the adjacent ends of the respective side plates, the upper 70 edges of the side plates being directed inwardly, the upper edges of the end plates between the inwardly disposed ends thereof being also directed inwardly to provide a base plate supporting means, a base plate 80 secured on said inwardly disposed flanges, and upstanding marginal flanges formed on the base plate, a plurality of side walls having their lower edges resting on the base plate and in engagement with said upstanding marginal flanges, and additional means 85 for holding the side walls in assembled relation.

In testimony whereof I affix my signature.

ROBERT L. MONTGOMERY.
